UNITED STATES PATENT OFFICE.

HENRY F. BROYLES, OF SHENANDOAH JUNCTION, WEST VIRGINIA, ASSIGNOR OF ONE-HALF TO CHARLES H. LIGHT, OF BOYCE, VIRGINIA.

IRONING-BOARD.

1,278,797.

Specification of Letters Patent. Patented Sept. 10, 1918.

Application filed December 9, 1916. Serial No. 136,035.

To all whom it may concern:

Be it known that I, HENRY F. BROYLES, a citizen of the United States, residing at Shenandoah Junction, in the county of Jefferson and State of West Virginia, have invented certain new and useful Improvements in Ironing-Boards, of which the following is a specification.

My invention relates to a device designed for the ironing of garments, linen and the like, and where provision is made for the ironing of sleeves of various garments and for the support of the iron, said device being capable of vertical adjustment to accommodate different users and being constructed of few parts so united that a rigid ironing board structure is obtained.

A leading object of the invention is to provide a board of the character described, the outer portion of which is entirely free of obstruction in order that shirts, skirts and the like may be arranged thereon, without the necessity of raising the board; and where special provision is made for the ironing of the sleeves of garments by a supplemental sleeve board which is permanently pivotally attached to the outer end of the main board so as to form an extension thereof.

Another object of the invention is to provide a simple means for the vertical adjustment of the board to suit the height of the person using said board and to so relate the parts that the board as a whole is firmly braced in all of its essentials, and is firmly sustained upon a wide footing, or base.

With the above and other objects in view my invention consists of the parts and the construction, arrangements and combinations of parts which I will hereinafter describe and claim.

In the accompanying drawing forming part of this specification and in which similar reference characters indicate like parts in the several views:

Figure 1 is a side elevation of an ironing board constructed according to my invention.

Fig. 2 is a front end view of the same.

Fig. 3 is a bottom plan view of the board in its folded condition.

In carrying out my invention I construct

the board of wood of suitable thickness and width, said board having substantially a uniform width for the greater portion of its length and thence tapering to the rear or outer end which is rounded in the usual manner, to allow a garment to be slipped over this end and onto the board in position to be smoothly ironed. The dimensions of the board are unimportant; a board about five feet long with a width of about twelve inches at the front and extending back for this width to a point slightly more than three feet from the rear end and thence tapering to the latter where the board is about $6\frac{1}{2}$ inches wide, will be found of suitable proportion for ordinary purposes.

In order to stiffen and strengthen this board, A, I secure across the under side of the same a short distance back of the front end, a head-block, B, and to the central portion of this block and extending along the longitudinal center of the board for considerable length, say for the greater portion of the total length of the board, is a brace, C, which I prefer to form of wood and set on edge. This brace at the front may be substantially as wide as the head-block and after extending rearwardly for a considerable distance at about this width it is gradually tapered from below toward the rear end, said brace being secured by screws, or otherwise, to both the head-block and to the board, A. The brace greatly strengthens the board in the direction of its length and gives rigidity to said board and reduces the springiness of the board to a minimum.

To the front end of the aforesaid brace, C, and proximate to the inner side of the head-block, is pivotally secured one end of a suitable adjustable stay-leg, D, the connection being in the form of a bolt, E, passing through the end of the stay-leg and the brace on the underside or bottom of the board. This stay-leg is preferably formed of two members, α and α' , which are spaced from each other a sufficient distance to allow the front end of the stay-leg to straddle the brace, C, and to be properly secured, said stay-leg having preferably a length substantially equal to the length of the board, A, and the members of the stay-leg being brought together and securely united at the

rear or free end, and which end is designed to be supported upon the floor at such a distance from the front leg of the board, and which I will presently describe, that a stable support is thus provided for the board when it is in use.

The front leg, F, of my ironing board is preferably formed of two similar members, b—b', of suitable width and thickness and which preferably are inwardly curved so that their upper ends may be brought well within the vertical plane or limits of the sides of the main ironing board, while the lower ends are spread a substantial distance apart so as to form a wide base which co-acts with the outer end of the stay-leg, C, when the device is set up for use, to form a three-point support, which will hold the board firmly in place against accidental collapse or displacement. The members of the front leg it will thus be observed flare downwardly and outwardly and form a downwardly diverging space, across which space near the lower end of the leg is a cross-bar, c, for substantially bracing and securing the leg portions against spreading movement and to rigidly unite one leg member to the other.

At a substantial distance from the upper ends of the spaced members of the front leg, said members are pivotally secured to the stay-leg D. To effect this suitable bolts, d, pass through each of the members of the front leg and through a corresponding member of the stay-leg, said bolts being secured by nuts, e, and the point of connection of the front leg to the stay-leg being a substantial distance from the pivotal point of the stay-leg, say about fourteen inches therefrom, whereby the upper ends of the front leg may be engaged under the main board to securely support the same at each side of the central brace, and said front leg is permitted to fold relatively to the stay-leg with the members of the front leg on the exterior of the stay-leg, when the ironing board is collapsed or in its folded position.

In addition to the foregoing I pivotally connect between the inner faces of the members of the stay-leg at a point substantially midway between the outer end of this leg and the point of pivotal connection of the front leg with said stay-leg, one end of an adjustable stay-brace, F, of such length that it will extend to and beyond the front leg when the parts are in their open or operative position, as indicated in Fig. 1, said stay-brace having formed in its underside at suitable distances apart, a plurality of notches, f, adapted to hook into engagement with a rod or bar, g, extending across the members of the front leg, whereby the front leg and the pivotal stay-leg are firmly connected against relative movement and the whole device made rigid when set up for use.

The provision of more than one notch in 65 the adjustable stay-brace enables me to adjust the vertical height of the table to suit the user, as will be well understood in this art.

In addition to the foregoing and in order to make the ironing board of more general use, I pivotally secure to the tapered rear end of the main board, A, a supplemental board, A', of smaller size and which preferably tapers from end to end, and which when 75 not in use may be folded under and parallel with the main board and which when extended or drawn out forms an extension of the main board, and which supplemental board will be found useful for ironing the 80 sleeves of shirts and other sleeved garments.

In order that the iron may be properly sustained in its relation to the board and without occupying any portion of the surface thereof, I pivotally secure under the head-end of the board at one side of the longitudinally extending brace, C, a support or shelf, H, which when not in use is contained under the main board, but when in use extends laterally from the main board so as to 90 form a rest for the iron.

From the foregoing description it will be seen that my board consists of a minimum of parts thereby materially reducing the cost of manufacture and providing a board of 95 great rigidity when in use and one which may be folded into a minimum area when not in use. The board also provides for the ironing of different sizes and kinds of garments and various pieces of linen and cloth, 100 and the separate sleeve board does not interfere with the passage of a garment over the main board when the sleeve board is inoperative and is folded under the main board.

While I have shown a preferred embodiment of the invention I do not limit myself thereto or to the proportions and exact design herein mentioned, but may make such changes thereover as do not depart from the spirit of the invention and which come with- 110 in the scope of the claim.

Having thus described my invention what I claim as new and desire to secure by Letters Patent is:—

An improved ironing board comprising a 115 main board or top; a brace extending edge-wise along the longitudinal central portion of the bottom for the greater part of the length thereof; a stay-leg formed of closely-spaced members whose upper ends straddle 120 said brace and lie substantially against the sides thereof, said members being pivotally connected to the brace at the head of the board and the lower ends of said members being converged and united; a front leg 125 formed of transversely spaced inwardly curved members adapted to closely straddle the stay-leg and the brace, said stay-leg and

members of the front leg crossing each other at a point about midway between the center of the said leg and the upper end thereof, a rod or bar fixed to the members of the 5 front leg and extending across the space between the lower portions thereof; and a stay-brace having one end pivotally secured be-

tween the closely spaced intermediate portions of the stay-leg and having the other end portion provided with notches to hook 10 into engagement with said rod or bar and adjustably secure the parts in position.

In testimony whereof I affix my signature.

HENRY F. BROYLES.
